UNITED STATES PATENT OFFICE.

CHARLES M. SMITH, OF HOT SPRINGS, ARKANSAS, ASSIGNOR OF NINE-TWENTIETHS TO ARTHUR JEFFERSON AND NINE-TWENTIETHS TO SIESEL HOWARD MATHEWS, BOTH OF HOT SPRINGS, ARKANSAS.

SAFETY CUT-OFF VALVE FOR GAS LINES.

Application filed September 16, 1926. Serial No. 135,931.

This invention relates to safety cut-off valves for gas lines.

An important object of the invention is to provide a device of this character which is entirely automatic in its operation, in so far as cutting off the gas supply is concerned, and which, when once positioned to cut off the gas supply, cannot be again opened without a manual operation.

10 A further object of the invention is to provide a valve including a cut off element which, in the open position thereof, presents a relatively large area to the gas pressure, so that it is retained in open position and which, in 15 the closed position thereof, presents a small area to the gas pressure, so that this gas pressure may not open the same.

A further object of the invention is to provide a device of this character which may be 20 readily and cheaply produced, which will be durable and efficient in service and a general improvement in the art.

These and other objects I attain by the construction shown in the accompanying 25 drawings, wherein for the purpose of illustration is shown a preferred embodiment of my invention and wherein:—

Figure 1 is a vertical sectional view through a control valve constructed in accordance 30 with my invention, the control bells being illustrated in solid lines in position permitting passage of gases through the valve and in dotted lines in the cut-off position;

Figure 2 is a section on the line 2—2 of 35 Figure 1.

Referring now more particularly to the drawings, the numeral 10 generally designates a casing having inlets 11 and 12 and an outlet 13. The inlets 11 and 12, only one of which 40 is employed, the other being a plug, communicate with an axial tube 14 extending upwardly into the casing from the bottom thereof. About this tube is formed an annular chamber 15 for the reception of a sealing fluid, such as 45 mercury. The upper end of the casing, for a purpose which will presently become obvious, is enlarged, as at 16. Inwardly of the casing wall a second annular chamber 17 is formed, the casing at its upper end enlarging at 50 18 to provide an enlargement of this chamber which is likewise intended for the reception of a sealing fluid. A cap 19 is provided for the casing and within the enclosure thus provided is mounted a bell 20, the side walls of

which extend into the chamber 17 and are 55 sealed by the liquid therein. This bell through a tube 21 which opens through the upper end of the wall of the bell supports a smaller bell 22, the side walls of which are adapted to extend into the chamber 15 and be 60 sealed by the fluid contained therein when the bell 20 has lowered to a predetermined degree. The lower end of the tube 21 is sealed to the bell 22 and the upper end thereof is provided with a cap 23 through which is directed 65 a stem 24 which loosely projects through an opening 25 formed in the cap 19 and is provided at the outer face of the cap with a head 26. At its lower end, the stem 24 is provided with a head 27 adapted to engage against the 70 under face of the cap 23 and so provide a means for elevating the bells 20 and 22. About this stem 24 between the cap 23 and the inner face of the casing cap 19 is a light 75 spring 28, this spring merely serving to cushion the bell 20 and prevent its engagement with the casing cap 19 under the influence of the gas pressure.

The operation is as follows: When the bells 20 and 22 are in the raised position, gas 80 may pass from either the inlets 11 or 12 to the outlet 13 and its pressure will be applied to both bells 20 and 22 to maintain these bells in elevated position. If the gas pressure is cut off, for any reason, the bells 20 and 85 22 will settle until the bell 22 enters the sealing fluid in the chamber 15. It will now be obvious that if the gas pressure is again turned on through the inlets 11 or 12, pressure will only be applied to the bell 22 and 90 this pressure will be insufficient to lift the bells 20 and 22 because of the weight of these bells. If, therefore, the gas cocks have been left opened during failure of the gas supply, there will be no unnoticed leakage, for it is 95 necessary that the operator lift the bells through the head 26 before a gas supply to the burners or jets can again be provided. The enlargements 16 and 18 provide for the rise of the sealing fluid as the bells 20 and 100 22 are moved downwardly thereinto.

It will be obvious that the construction hereinbefore set forth is capable of a considerable range of change and modification without materially departing from the spirit 105 of the invention and I accordingly do not limit myself to such specific structure except as hereinafter claimed.

I claim:—

1. In a safety gas cut-off valve and in combination, a casing having an inlet opening through and extending upwardly from the bottom thereof, a wall surrounding the inlet and combining therewith to produce an open-topped chamber, the upper end of the wall being flared to provide an enlargement of the chamber, a second wall arranged inwardly of and in spaced relation to the casing 5 wall and combining therewith to produce an open-topped chamber the upper end of which extends considerably above the upper end of the inlet, the casing wall being enlarged to enlarge the upper end of said chamber, 10 a pair of bells within the casing and having their lower ends adapted for extension into said chambers, said bells being connected for simultaneous movement, an outlet for the casing at the bottom thereof, said chambers 15 having a sealing fluid therein, the connection between the bells comprising a tube, a cap closing the upper end of the tube, a rod reciprocable through the upper end of the casing extending through the cap into the 20 tube and provided at its lower end with a head and a spring surrounding the rod between the casing top and said cap.
2. In a safety gas cut-off valve and in combination, a casing having an inlet opening through and extending upwardly from the bottom thereof, a wall surrounding the inlet 25 and combining therewith to produce an open-

topped chamber, the upper end of the wall being flared to provide an enlargement of the chamber, a second wall arranged inwardly of and in spaced relation to the casing 30 wall and combining therewith to produce an open-topped chamber the upper end of which extends considerably above the upper end of the inlet, the casing wall being enlarged to enlarge the upper end of said chamber, 35 a pair of bells within the casing and having their lower ends adapted for extension into said chambers, said bells being connected for simultaneous movement, an outlet for the casing at the bottom thereof, said chambers 40 having a sealing fluid therein, the connection between the bells comprising a tube, a cap closing the upper end of the tube, a rod reciprocable through the upper end of the casing extending through the cap into the 45 tube and provided at its lower end with a head and a spring surrounding the rod between the casing top and said cap.

In testimony whereof I hereunto affix my signature.

CHARLES M. SMITH.
